UNITED STATES PATENT OFFICE.

ROBERT R. HAGE, OF CULBERTSON, MONTANA, ASSIGNEE OF ONE-HALF TO OSCAR HAGE, OF CULBERTSON, MONTANA.

LIQUID-DISPENSING APPARATUS.

1,165,667.

Specification of Letters Patent. Patented Dec. 28, 1915.

Application filed June 22, 1914. Serial No. 846,500.

To all whom it may concern:

Be it known that I, ROBERT R. HAGE, a citizen of the United States, residing at Culbertson, in the county of Sheridan and 5 State of Montana, have invented certain new and useful Improvements in Liquid-Dispensing Apparatus; and I do hereby declare the following to be a full, clear, and exact description of the invention, such as 10 will enable others skilled in the art to which it appertains to make and use the same.

My invention has for its object to provide an improved liquid-measuring apparatus; and, to this end, it consists of the novel devices and combinations of devices herein-after described and defined in the claims.

In the accompanying drawings, which illustrate the invention, like characters indicate like parts throughout the several 20 views.

Referring to the drawings, Figure 1 is a view in front elevation of the improved liquid-measuring apparatus, some parts being broken away and some of the exposed 25 parts being shown in section; Fig. 2 is a side elevation of the same; Fig. 3 is a transverse vertical section, taken on the line $x^3 x^3$ of Fig. 2; Fig. 4 is a detail view, principally in vertical section, taken on the line $x^4 x^4$ of Fig. 3 on an enlarged scale; and Fig. 5 is a view, partly in front elevation and partly in 30 section, of the apparatus, taken on the line $x^5 x^5$ of Fig. 2, on an enlarged scale, some parts being broken away and some parts 35 being shown in different positions by means of dotted lines.

The numeral 1 indicates a rectangular liquid holding receptacle, supported on legs 2. As shown, liquid is supplied to this 40 receptacle from an underground tank 3, through a delivery pipe 4, which discharges into the top of said receptacle. A pump, indicated as an entirety by the numeral 5, is provided for pumping the liquid from 45 the tank 3, through the pipe 4, into the receptacle 1. Interposed in the pipe 4, just above the pump 5, is a check valve 6 arranged to prevent return flow of the liquid 50 to the tank 3. Also interposed in the pipe 4, close to a point where the same discharges 55 into the receptacle 1, is a horizontally extended two-way plug valve 7, having a long stem 8, journaled in a bearing 9 on top of the receptacle 1. To prevent the receptacle 1 from filling with liquid above a predeter-

mined height, the same is provided with an overflow pipe 10, which taps the said receptacle, just under its top, and is arranged to deliver the overflow into the tank 3. This overflow pipe is highly important in order 60 that the receptacle 1 will always be filled with a given amount of liquid, and no more.

Liquid is dispensed from the receptacle 1 through a delivery pipe 11, return-bend discharge pipe 12, and a nozzle 13. The delivery pipe 11 is swiveled at its receiving end in a stuffing box 14, secured to a depending nipple 15 on the bottom of the receptacle 1. The outer end of this pipe 11 terminates in a bearing sleeve 16, having a central chamber 17 and stuffing boxes 18. This bearing sleeve 16 is located at a point below the bottom of the receptacle 1. The nozzle 13 is bolted to a horizontally extended arm 19, integrally formed with the bearing sleeve 16, 70 and is provided at its receiving end with a stuffing box 20, which is axially aligned with the bearing sleeve 16.

As best shown in Figs. 2 and 4, the return-bend discharge pipe 12 comprises a crown 80 21, and receiving and delivery legs 22 and 23, respectively. The free ends of these legs 22 and 23 are bent horizontally outward to afford a pair of journals 24 and 25, respectively. The journal 24 is swiveled in the bearing sleeve 16, works through the stuffing boxes 18, and is closed at its free end. Said journal is also provided with ports 26, which afford communication between the chamber 17 and the receiving leg 22. The journal 25 is swiveled in the stuffing box 20 of the nozzle 13. Upper and lower stops 27 and 28, respectively, on the receptacle 1, limit the swinging movement of the discharge pipe 12 to substantially 90 degrees. When 85 in a vertical position, the pipe 12 engages the stop 27 and its crown 21 extends above the top of the receptacle 1, so that no liquid from the receptacle can flow therethrough. To drain the receptacle 1, the overflow pipe 12 may be turned into a substantially horizontal position and its further downward movement is limited by the stop 28. Obviously, when the crown of the overflow pipe 12 is turned below the liquid line in the receptacle 1, the liquid will flow through said pipe under the action of gravity until the 90 level of the liquid in the receptacle is lowered to the altitude indicated by the crown 21. To prevent a siphoning action of the 105 110

liquid through the discharge pipe 12, a vent pipe 29, preferably of flexible material, taps the crown 21 and extends to a point above the receptacle 1.

5 An altitude gage 30 has communication, at its lower end, with the chamber 17 through a port 31, formed in the bearing sleeve 16. The lower end of this gage is mounted in a stuffing box 32 on the bearing sleeve 16 and its upper end is mounted in an arm 33, integrally formed with said sleeve.

Secured to the face of the receptacle 1 is a segmental dial 34, having formed in its periphery a plurality of longitudinally spaced notches 35. Pivoted to the crown 21 is a spring-pressed latch 36, having attached thereto a tooth 37, which works through a bearing 38 on the crown 21 for co-operation with the notches 35 to lock the said crown 20 in different altitudes. Underlying the hand portion of the latch 36 is a finger piece 39, integrally formed with the crown 21 by which the discharge pipe 12 may be swung to carry its crown 21 into different altitudes.

25 As best shown in Fig. 5, the dial 34 is divided into a plurality of zones 40. Each zone is graduated to indicate quarts and gallons and the markings read from the top of the receptacle down, and the zero points of the several zones are in stepped arrangement. Co-operating with the graduations of the several zones is an indicator 41, slidably mounted on a rod 42, carried by the receiving leg 22 of the overflow pipe. Secured to 35 the indicator 41 is a spring pawl 43, adapted to enter any one of a plurality of longitudinally spaced notches 44 in the rod 42. It will be noted that the lines indicating the different zones are struck from the same

40 center as the axis of the discharge pipe 12 and there is one notch 44 for each zone, so that the indicator 41 may be set to travel over the face of any one of the several zones. The graduations of the several zones are so 45 graded that when the indicator 41 is over the zero point of the lowermost zone the discharge pipe 12 is in a vertical position, as shown in Fig. 1, and the receptacle is full of liquid. From this point the successive 50 zero points are stepped down, with respect to the receptacle, and outward, with respect to the dial, and the distance between adjacent zero points indicates one quart of the contents of the receptacle 1. For instance, 55 if the indicator 41 is moved from one zero point to the next lower zero point, the crown 21 will be set at an altitude to permit one quart of the liquid to flow therethrough.

To prevent any of the liquid from being 59 drawn from the receptacle 1 while the same is being filled, and to prevent the receptacle from being filled while any of the liquid is being drawn therefrom, is provided a lock bolt 45, for alternately securing the valve 7 and discharge pipe 12 in operative and in-

operative positions. This lock bolt 45 is mounted for vertical sliding movement in a pair of vertically spaced bearings 46, secured to one side of the receptacle 1. Co-operating with the upper end of the lock bolt 45 is a notched sector 47, rigidly secured to the outer end of the valve stem 8, and co-operating with the lower end of said lock bolt 45 is a notched sector 48, rigidly secured to the outer end of the journal 24. Both 70 of these notched sectors 47 and 48 have integrally formed therewith radially projecting stop lugs 49, which prevent the same from passing out of engagement with the ends of the lock bolt 45. The notches of 80 the sectors 47 and 48 are reversely formed and the lock bolt 45 is of such a length that when one end thereof is seated in one of the notches of said segments the other end thereof will rest on the periphery of the respective notched segment and allow free oscillatory movement thereof. The valve 7 is locked closed by the plunger rod 45 while the pipe 12 is free for swinging movement.

Mounted on the nozzle 13 is a register 50, actuated by a one-way acting dog 51 carried by the discharge pipe 12. This register may be of any desired construction and is provided for indicating the total amount of liquid passing through the nozzle 13. 95 The dog 51 is so arranged that a downward swinging movement of the discharge pipe 12 will actuate the register, and an upward swinging movement of said pipe will render said dog inoperative. In actual usage, this 100 dog and the co-operating element of the register will be covered with a casing so that the same cannot be tampered with.

Operation: The operation of the improved measuring apparatus may be briefly 105 described as follows: The receptacle 1 is filled with liquid from the tank 3 in a manner previously described, at which time the discharge pipe 12 is locked in a vertical position by the lock bolt 45, and the valve 7 110 is open. If it is desired to draw one gallon of the liquid from the receptacle 1, the lock bolt 45 is moved into a position to release the discharge pipe 12 and lock the valve 7 closed. The discharge pipe 12 is then swung downward until the indicator 41 overlies the numeral indicating one gallon, in which 115 position said indicator is shown by means of dotted lines. This position of the discharge pipe 12 will set its crown at an altitude to permit one gallon of the liquid to flow therethrough, and out of the nozzle 13. The overflow pipe will remain in this position until it is desired to draw a further 120 amount of liquid from the receptacle. For instance, if it is desired to draw one and one-half gallons of liquid from the receptacle, the indicator 41 is slid upward on the rod 42 until it overlies the zero point in the same radial line with the numeral indicating 125

one gallon from which point the indicator has just been moved. This permits the next measurement to be made from zero, thus avoiding mistakes in addition which might 5 occur in adding the amount required to the amount previously drawn. From this last noted zero point, the discharge pipe 12 is swung downward until the indicator 41 over-lies the numeral indicating one and one-half 10 gallons in the same zone with said zero point. It will also be noted that the graduations in the lowermost zone indicate the total amount of liquid drawn from the receptacle. In these various positions of the 15 discharge pipe 12, the same is locked to the dial 34 by the latch 36, in a manner previously described.

From the foregoing description it is evident that the improved liquid measuring 20 apparatus may be used for dispensing various liquids and it is thought that the same will be found highly serviceable in dispensing gasoline for use in motor-driven vehicles.

25 What I claim is:

1. The combination with a liquid dispensing receptacle, having a valve-equipped filling pipe, of a return-bend discharge pipe, having its receiving leg in communication 30 with said receptacle and having its crown arranged to be set at different altitudes, and means for locking the valve closed when the discharge pipe is free and for locking the discharge pipe when the valve is open.
- 35 2. The combination with a liquid dispensing receptacle, having a valve-equipped filling pipe, of a return-bend discharge pipe, having its legs swiveled for movement on a common axis, the receiving leg of said pipe

being in communication with said receptacle, a nozzle arranged to receive from the delivery leg of said pipe, a pair of notched segments secured, one to the stem of said valve and the other to said pipe at the axis thereof, and a lock bolt engageable alternately with said notched segments. 40

3. The combination with a liquid dispensing receptacle, of a return-bend discharge pipe, having its legs swiveled for movement on a common axis, the receiving leg of said pipe being in communication with said receptacle, a nozzle arranged to receive from the delivery leg of said pipe, a dial secured 50 to said receptacle and having graduated zones, and a sliding indicator mounted on 55 said pipe for coöperation with the graduations in said zones and for movement transversely thereof.

4. The combination with a liquid dispensing receptacle, of a return-bend discharge 60 pipe, having its legs swiveled for movement on a common axis, the receiving leg of said pipe being in communication with said receptacle, a nozzle arranged to receive from the delivery leg of said pipe, a dial secured 65 to said receptacle and having graduated zones, a sliding indicator mounted on said pipe for coöperation with the graduations in said zones, and means for locking the crown of said pipe to said dial at different 70 altitudes.

In testimony whereof I affix my signature in presence of two witnesses.

ROBERT R. HAGE.
